DESIGN FOR AN AUTOMOBILE RADIATOR CAP

Ernst Olsson, Brooklyn, N. Y.

Application December 5, 1939, Serial No. 88,701

Term of patent 7 years

To all whom it may concern:

Be it known that I, Ernst Olsson, a citizen of the United States, residing at Brooklyn, in the county of Kings and State of New York, have invented a new, original, and ornamental Design for Automobile Radiator Caps, of which the following is a specification, reference being had to the accompanying drawing, forming part thereof, and in which:

Figure 1 is a front elevational view of an automobile radiator cap showing my new design; and

Figure 2 is a vertical mid-sectional view through the same.

I claim:

The ornamental design for an automobile radiator cap, as shown.

ERNST OLSSON.
